UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,255,887.

Specification of Letters Patent. Patented Feb. 12, 1918.

Application filed June 3, 1911. Serial No. 631,314.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

My invention relates to electric switches.

It more especially relates to electric switches of the type known as multi-circuit switches described and claimed in my co-pending application Serial No. 628,157, filed 15 May 19, 1911, patented Nov. 30, 1915, No. 1,162,076.

Among the objects of my invention is to provide an improved electric switch of the 20 multi-circuit type. A further object of my invention is to provide an improved electric switch arranged to control any desired number of circuits and equipped with a plurality of self-contained switch mechanisms connected together to form a single unit which 25 may be readily removed from or inserted in the switch casing as desired. Other objects and advantages of my improved construction will hereinafter appear.

30 In the accompanying drawings I have illustrated one form which my invention may assume in practice. My invention, however, is not limited to this specific form, but may assume other forms.

35 In the views of these drawings:—

Figure 1 shows a central sectional view through an assembled switch mechanism.

Fig. 2 shows a transverse sectional view on line 2—2 of Fig. 1.

40 Fig. 3 shows a side elevation of one of the parts of the switch casing and a portion of the self-contained switch mechanism in position in the same.

In these views I have illustrated a switch 45 casing of substantially the same construction as the switch casing illustrated in my co-pending application above-mentioned. This casing includes two halves 1 and 2 of insulating material and a cap 3. The two halves 50 are arranged to be held together as illustrated in Fig. 1 and house between them a plurality of self-contained switch mechanisms 5 of the type described in my co-pending application Serial No. 630,388, filed 55 May 31st, 1911, patented Dec. 7, 1915, No.

1,162,866, which are connected together to form a unit.

As in the previous construction the push buttons for these switch mechanisms extend through openings in the opposite sides of 60 the switch casing. In this instance, however, instead of securing the parts of the casing together by a single screw between the switch mechanisms, the parts of the casing are secured together by connecting the 65 same to the opposite ends of the self-contained switch mechanisms 5. One of the casing members is attached to one or more of the switch mechanisms by means of screws 70 having their heads seated in suitable recesses in the outer surface of the casing and their shanks engaging threaded perforations in one of the end members of the frame of each switch mechanism. The other casing member is secured to one or more of the side 75 members of the frames by suitable taps 7 seated in suitable recesses in the outer surface of the casing. In this construction instead of providing a septum in one of the base members to separate the switch mechanisms I preferably provide the base members with rectangular shaped recesses 8 and 80 9, which are of substantially the same depth and when the casing is assembled provide a chamber to house the switch mechanisms. 85 In a preferred form the switch units employed are connected together by some suitable means such as, for instance, a rivet 10 passed through their adjacent side members. Thus it is seen that the switch mechanisms 90 are united so that they are in reality inclosed in a single frame and in effect constitute a single unitary mechanism. In a preferred form the ends of the adjacent side members of the frames are cut off, as shown at 11, so that they abut against the wall of one of the base members and serve to position the unit in the casing, and the casing members are provided with suitable recesses arranged to receive the end members of the unit frames, 95 so that the units fit snugly within the casing.

In this construction the terminal contacts 12, 13 and 14 are of the same general construction as those described in my co-pending application Serial No. 628,157, filed May 19, 1911, Patent No. 1,162,076, and have their upper ends carried in one of the parts of the casing in the same manner. In this instance, however, the shanks of the terminals instead of being entirely flat as therein 100 110

shown are twisted near their upper ends at 15, so that the edges of the terminal members are presented to the contactors of the switch mechanisms. The shanks of these 5 terminal members are seated in the insulating end members of the switch units on opposite sides of the operating members of the switch mechanism as illustrated in Fig. 3, and are preferably provided with extensions 10 extending through this end member and riveted to a plate on the opposite side of the same, as described in my co-pending application Serial No. 630,388, filed May 31st, 1911, Patent No. 1,162,866. Terminal 15 contact 14 in this construction, however, is not carried entirely by the insulating end members, but is bent at about its middle point and extends upward parallel to the other contacts in a separate recess 16, having 20 a wall 17 separating it from the body of the chamber and an opening 18 at its lower end through which the bent portion of the terminal passes. The lower end of this terminal, however, is carried by the insulating 25 end member of the lower unit in the same manner as the other contacts.

When it is desired to operate the switch mechanism to control a single circuit all that is necessary to do is to push in one of the 30 push buttons. As in the previous construction, the terminal contact 12 is arranged to act as the common terminal for one or more circuits. When one of the upper push buttons is actuated one circuit will be controlled, while when one of the lower push buttons is actuated another circuit may be controlled, and as in the case of the previous construction the device may be adapted to the control of any desired number of 35 circuits. It is, of course, also obvious that more than two switch mechanisms may be employed if desired and that each of these switch mechanisms may be used to control one or more circuits.

40 By my improved construction I have provided a switch arranged to control one or more circuits in which the entire switch mechanism is self-contained and may be readily inserted or removed when desired. 45 When it is desired to take out the switch mechanism all that is necessary to do is to remove the screws and taps holding the parts of the casing together, and when this

is done the entire switch mechanism may 55 be removed. Further, by the improved arrangement of the terminal contacts these terminal contacts may also be removed with the switch mechanism, so that when the parts of the base are separated to obtain access to the switch mechanism the entire 60 series of units may be removed as the parts are separated. Further, the parts of the units themselves may be readily separated, since these parts are held together by the 65 resilient engagement of the metallic parts with the insulating base.

While I have in this application described one form which my invention may assume, my invention is not limited to this specific form, but may assume other forms, and I 70 consequently wish to cover in this application all of those various other forms falling within the scope of my invention, as defined by the following claims.

What I claim as new and desire to secure 75 by Letters Patent is as follows:

1. In an electric switch, a plurality of snap switch mechanisms, a frame inclosing the same to form a unit and terminal contacts carried by said unit, one of said terminal contacts being arranged to serve as a terminal for a plurality of circuits.

2. In an electric switch, a plurality of snap switch mechanisms, end members arranged to limit the movement of the same, 80 side members connecting said end members to form a plurality of frames inclosing said switch mechanisms, means for connecting said frames to form a single unitary frame, and a casing attached to said unitary frame.

3. In an electric switch, a plurality of snap switch mechanisms, end members arranged to limit the movement of the same, 85 side members extending through one of said end members arranged to connect said end members to form a plurality of frames, means for connecting said frames to form a single unit and a casing inclosing said unit and attached to its opposite ends.

In witness whereof, I have hereunto subscribed my name in the presence of two witnesses.

CHARLES J. KLEIN.
